UNITED STATES PATENT OFFICE

ABDEL JOHN PETERSON, OF CHICAGO, ILLINOIS

OUTLET LOCATOR

Application filed April 16, 1925. Serial No. 23,489.

My present invention relates to improvements in outlet locators, made in the form of outlet covers for use in conjunction with outlet boxes, and my invention has for its para-
5 mount object the provision of a device of this character which will be economical in manufacture and highly efficient in use.

More specifically, my invention relates to an outlet locator adapted to be used in place of the usual outlet box cover and constructed with a front wall for completely closing the entrance to the outlet box to keep out foreign matter; and the principal object of my invention is the provision of a device of this character in which the inclosing front wall is constructed to include a separable portion having a projecting locator member adapted to mark the location of the outlet box if the inclosing wall becomes smeared with plaster or other material and adapted also to serve as means for receiving the force necessary for the removal of the separable portion when it is desired to have access to the outlet box.

25 Other objects will appear hereinafter.
The invention consists in the combinations
and arrangements of parts hereinafter de-
scribed and claimed.

The invention will be best understood by reference to the accompanying drawing forming a part of this specification, and in which

Fig. 1 represents a fragmental section through a wall, showing my outlet cover and locator associated with an outlet box arranged in the wall;

35 Fig. 2 represents a face view of the parts shown in Fig. 1;

Fig. 3 represents an end view of the weakened closure plate as it appears when separated from the outlet box cover;

40 Fig. 4 is a face view of the part shown in Fig. 3; and

Fig. 5 is a central sectional view through an outlet box cover provided with a modified form of weakened closure plate.

45 With more particular reference to the parts
illustrated in the accompanying drawing, 6
represents an outlet box of any customary
type, adapted to be installed in the wall 7
in the usual way, to afford a container for
50 the usual electric switch and wires. 8 de-

notes the customary conduits which lead through the wall to the outlet box. It will be understood that the outlet box is installed in the wall before the plaster 8' or other suitable surfacing material is applied to the wall.

The preferred embodiment of my invention as illustrated in the accompanying drawing comprises an outlet box cover 9 formed all around with the usual flange 10 adapted to fit flat against the flange 11 of the outlet box 6 and to be secured thereto by means of suitable bolts 18 and 19. The box 6 is secured in position by any usual means and is also held in position by means of the conduits 8 which are in turn securely held by suitable means (not shown). The plaster 8' is held by laths 17, which are suitably secured by studding 7 and over the plaster 8' is a finished coat 20 which may extend over the outlet box covering, as shown in Figure 1. This outlet box cover 9 is made with a circular front wall or plate 12 for closing the entrance into the outlet box 6 to prevent portions of the plaster from entering thereinto during the plastering operations, and said front wall or plate is arranged to be removed or knocked out along separating lines 13 after the plastering operations have been completed and when it is desired to have access to the outlet box for connecting up or installing such wiring and appliances as conditions may require. The wall or closure plate 12 is made with an outwardly projecting member 14 which is employed as means for indicating or marking the position of the outlet box where the wall

or closure plate 12, as usually happens, becomes smeared or surfaced with plaster and which is also employed as means for receiving pressure or light blows from a hammer when the wall or closure plate is to be removed or knocked out. Preferably and as shown, the weakened closure plate 12 consists of an insert and the separating lines 13 consist of edges 15 bevelled inwardly of the cover and in a direction away from the locator member 14, so that the separating lines 13 will readily give away permitting the closure plate to be driven inwardly of the cover when force is exerted upon the free end of the member 14. In its production, the closure plate 12 is pref-

erably made in the first instance as an integral part of the outlet cover 9. It is then sheared or punched out so as to produce the bevelled edges 15, whereupon it is expanded and then finally resecured in its original position by a drive fit. While the closure plate is preferably produced in this manner, it will be obvious that it may also be produced by providing perforated lines, although this method results in the provision of undesirable ragged edges.

In Fig. 5 I illustrate the closure plate 12 not only weakened along the separating lines 13 but also weakened along the similarly beveled separating lines 16 which encircle the base of the locator member 14. When the closure plate 12 is thus twice weakened, the separating lines 16 are produced so as to have less strength than the separating lines 13, so that the locator member 14 may be driven out along the lines 16 without separating the plate along the lines 13. This is accomplished by means of the cutting die which spreads the metal slightly at 16 in the cutting process, so that when the cut out portions are forced back into position, the separating line 16 is much weaker than the separating line 13. If desired, the separating lines 13 may be omitted entirely and the closure plate weakened only at the separating lines 16.

From the foregoing description, taken in connection with the accompanying drawing, it will be understood by those familiar with this art that my improved outlet cover will prevent plaster and all foreign matter from entering into the cavity of the outlet box 6 during the plastering operations; that where the wall or closure plate 12 is smeared with plaster during the plastering operations, the projecting member 14 will show the position of the outlet box; and that where it is desired to connect up or install wiring or appliances, access to the box may be had by forcing or knocking out the wall or plate 12. It may be remarked here that where buildings are rapidly erected, the plasterers are sometimes set to work before the electricians have had an opportunity to install the switches or other appliances in the outlet boxes. Where this condition prevails, covers weakened only along the lines 13 are used with a view to providing openings appropriate for installing the switches and necessary accessories. Where, on the other hand, the leads have been installed prior to applying the plaster and it appears that small openings for the accommodation of plugs or leading out wires are all that will be required, covers weakened only along lines 16 may be employed. In cases where there is doubt as to the permanency of the installations, that is, where it may be desired to change the installations at some future time, covers with both sets of separating lines 13 and 16 are

employed, the separating lines 16 providing small openings for the plugs or leading out wires of the installations already housed in the outlet box, while the separating lines 13 make provision for the contemplated future changes.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. An outlet box cover including a closure plate frictionally retained in an opening in said plate, said closure plate having a projecting boss serving when said plate is embedded in a plastered surface as a means to locate said outlet box and also as an instrumentality in facilitating the removal of said closure plate from said box by percussion and pressure.

2. An outlet box cover having means for attachment to the outlet box and provided with a plate for closing an entrance into the outlet box, said plate comprising an element imbedded in a plastered surface and supported from said plate while being held in position in the entrance of the plate by frictional engagement therewith, and a member on said element for aiding the removal of the element from said plate.

3. An outlet box cover including a part imbedded in a plastered surface and adapted to be attached to the outlet box, said part having an aperture the circumscribing edges of which are bevelled, and a plate for closing said aperture, said plate having a bevelled edge registering and being held in frictional engagement with the bevelled edge of the aperture of said part, a projection formed integral with said plate for indicating the position of the aperture, said projection being adapted to receive pressure for displacing the said plate.

In testimony whereof I have signed my name to this specification.

ABDEL JOHN PETERSON.
